THERMAL SWITCH

Charles J. Hardison, deceased, late of St. Petersburg, Fla., by Betty Hardison, administratrix, Jacksonville, Fla.; said Charles J. Hardison, assignor of fifty-one per cent to Maxey D. Moody, Jacksonville, Fla.

Original application March 23, 1933, Serial No. 662,401, now Patent No. 1,968,828, dated August 7, 1934. Divided and this application June 20, 1934, Serial No. 731,514.

1 Claim. (Cl. 200—122)

This invention relates to electrical switches and more particularly to a thermal switch especially designed for use in connection with automatic oil and temperature control systems of the type shown and described in my co-pending application, Serial No. 662,401, filed in the United States Patent Office March 23, 1933, now Patent No. 1,968,828 and of which the present application is a division.

10 The object of the invention is to provide a switch which will automatically close a circuit and successively illuminate a warning light and stop the engine of a motor driven conveyance should, for any reason, the temperature of the fluid in the cooling system become so high as to endanger the bearings, cylinder walls and other parts of said engine.

15 A further object of the invention is generally to improve this class of devices so as to increase their utility, durability and efficiency.

20 In the accompanying drawing, forming a part of this specification, and in which similar numerals of reference indicate corresponding parts in all the figures of the drawing:

25 Figure 1 is a top plan view of a thermal switch constructed in accordance with the present invention, the casing or housing of the switch being shown in section.

Figure 2 is a vertical sectional view of the 30 same.

Figure 3 is a transverse sectional view taken on the line 3—3 of Figure 1.

Figure 4 is a detail perspective view of the support for the leaf spring.

35 The thermal switch, forming the subject-matter of the present invention, comprises a base 5 of insulating material having a metal plate 6 mounted thereon and provided with an upstanding lug 7 on which is mounted, for turning movement, a metallic stud 8 preferably angular in cross section and to which is secured one end of a switch arm 9 having a terminal contact member 10 thereon which coacts with a similar contact member 11 mounted on an upstanding bracket 12 secured to the base, as shown. The contacts 10 and 11 are normally closed and in order to hold them in closed position a leaf spring 13 is provided, one end of which is seated in a kerf 14 in the stud 8, while the other end thereof is seated in a slot 15 formed in an upstanding bracket 16 which is secured to the base 5 in any suitable manner, as by a clamping screw 17. At one end of the base 5 are spaced binding posts 18 and 19 to which are connected the terminals 20 of a motor circuit, as shown and described in

my co-pending application previously referred to. Secured to the binding post 18 is a conductor 21 leading to and connected with the stud 8 by a clamping screw 22, the other binding post 19 having a conductor 23 connected therewith and leading to the base of the bracket 12. Disposed at one end of the base 5, opposite the binding posts 18 and 19, is a single binding post 25 connected by a conductor 26 with a warning light (not shown) and to which binding post is secured a 10 relatively fine resistance wire 27, the intermediate portion of which is coiled or wrapped around the switch arm 9, as indicated at 28, and is connected with the adjacent end of the conductor 21 by the screw 22. The purpose of the coil 28 is to heat 15 the switch arm which is of bimetallic construction and expand the same as indicated by dotted lines in Figure 1 and thus break the contact between the contact members 10 and 11 so as to interrupt the motor circuit and automatically 20 stop the engine.

Under normal conditions, the motor circuit to the engine is closed so that the engine is free to operate in the usual manner. Should the temperature of the cooling system become too high 25 so as to endanger the bearings and other parts of the engine, a portion of the current will flow through the conductor 21 and thence through the coil 28 so as to heat the switch arm 9. As the switch arm becomes heated it will expand and 30 open the motor circuit and successively illuminate the warning light and stop the engine, as fully set forth and described in my co-pending application which has matured into patent 1,968,828, issued August 7, 1934.

35 It will be noted that the screw 22 not only serves to connect the wires 21 and 27 to the stud 8, but as the screw extends through the inner ends of the spring 13 and switch arm 9 it also serves to firmly anchor said spring and 40 switch arm to the stud.

45 While the thermal switch is principally designed for use in connection with automatic oil and temperature control systems for motor-driven conveyances, it will, of course, be understood that said switch may be used wherever a switch of this type is found applicable or desirable.

Having thus described the invention, what is 50 claimed is:

A thermal switch comprising an insulating base, a bracket of conductive material secured to said base and having an upstanding arm carrying a stationary contact, a plate secured upon said base and carrying an upstanding pin, a stud 55

mounted loosely upon said pin and formed with kerfs spaced from each other at opposite sides of the pin, a switch arm having one end seated in one kerf and having a contact at its other end opposite the stationary contact, the portion of the arm between the stud and bracket being spaced upwardly from the base an appreciable distance, a second bracket carried by said base, a leaf spring having one end secured in the second kerf of the stud with its other end secured to the second bracket, said spring normally holding the switch arm in position for engagement of its contact with the stationary contact, binding posts having conductors leading therefrom to the

stud and first mentioned bracket, another binding post carried by the base and having a conductor leading therefrom, and a heating coil having its ends secured to the stud and last mentioned conductor, said coil surrounding the switch arm and adapted when heated to expand the switch arm and move its contact out of engagement with the stationary contact and interrupt flow of current between the first mentioned conductors.

10

BETTY HARDISON,
Administratrix of the Estate of Charles J. Hardison, Deceased.
